[57] **CLAIM**

The ornamental design for a hand-held laser scanner, as shown and described.

DESCRIPTION

FIG. 1 is a top, front, left side perspective view of a hand-held laser scanner showing our new design; FIG. 2 is an enlarged top plan view thereof; FIG. 3 is an enlarged left side elevational view thereof; FIG. 4 is an enlarged front elevational view thereof; FIG. 5 is an enlarged rear elevational view thereof; FIG. 6 is an enlarged bottom plan view thereof. The right side view of the hand-held laser scanner is identical to the left side elevational view shown in FIG. 3.

FIG.4

FIG.5

FIG.6
